UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

BOTTLE CAP.

Application filed October 30, 1924. Serial No. 746,782.

This invention relates to certain improvements in closure disks or so-called bottle caps equipped with top pull tabs normally depressed in the cap flush and parallel with the top surface thereof; and the objects and nature of the invention will be readily understood by those skilled in the art in the light of the following explanations of the accompanying drawings that illustrate what

10 I now believe to be the preferred mechanical expressions or embodiments of my invention from among other forms within the spirit and scope thereof.

A bottle cap now on the market is 15 equipped with a pull handle formed by a separate strip of tough paper secured on the top surface of the cap by a staple driven through the strip and cap and clinched at the bottom side of the cap. This attached

20 handle cap is expensive because of the added cost of the attached paper strip, and furthermore the attached paper strip forms an upward projection from the top face of the cap rendering it difficult to properly stack

25 such caps in tubes and preventing the use of such caps in bottle capping machinery. It has been proposed to seat the attached handle of such cap in a previously formed depression in the cap, in an effort to overcome the before mentioned difficulties by 30 depressing the handle. According to one depressed-handle plan, the cap making machinery grinds or cuts out and removes the material of the cap for about one half the

35 thickness of the cap to form a radial seat or depression in the cap top extending through the peripheral edge of the cap. The machinery then feeds the handle-forming strip of paper across the cap and into the

40 depression thus formed and staples the strip to the cap by a staple passing through the strip and the weakened thin portion of the cap that forms the floor of the depression, and then cuts off the paper strip at the outer 45 end of the depression flush with the peripheral edge of the cap. According to another depressed-handle plan, it is proposed to form the attached handle receiving depression, by compressing the paper at that

50 point to say about one half its original thickness. These two depressed handle plans present the original difficulty of the added cost of the separate handle forming paper strip. The first mentioned depressed

55 handle plan also, presents the difficulty of

anchoring the added handle strip to the thin weakened portion of the cap at the floor of the depression, with resulting liability of the staple tearing through the thin floor under extracting pull; also this first plan 60 does not fully remove upward projections from the cap top as the securing staple causes trouble in capping machinery. The second mentioned depressed handle plan proposes to form the depression by compressing the paper material of the cap, but as those skilled in paper material and the peculiarities thereof, well know that a depression so formed is not permanent but is 65 fugitive and but temporary, as the compressed paper tends to swell to its original condition particularly when subjected to moisture. This last mentioned plan does not solve the problem as the natural swelling of the compressed paper elevates the attached handle strip to a plane above the 70 level of the top surface of the cap and tends to strip the staple from the cap.

75 Another type of paper bottle cap in use, overcomes the added expense of the separate 80 stapled paper strip and certain other disadvantages of the hereinbefore described handled caps, but presents certain disadvantages peculiar to itself. This last mentioned type provides a depressed pull tab formed 85 by a thin portion of the cap outlined by a faint shallow U-shaped slit, and then by a blade split horizontally entirely free of the cap except at the base of the tab and up to a transverse staple driven through the 90 cap.

95 One of the objections to these bottle caps having depressed pull tabs integral therewith and split from the upper portions of the caps, is the difficulty experienced by the average individual in reaching or getting at the free end of this faintly outlined tab to 100 initiate the elevating swing or movement of the tab from the recess in the cap in which the tab is normally snugly fitted with its edge covered and concealed, and another objection is due to the fact that many individuals are not familiar with the construction of such caps and do not observe them, when in the bottle mouth, with sufficient 105 understanding or intelligence to even appreciate the presence of the depressed tab lightly outlined by a barely visible slit or cut, or if the outline is observed to understand that the free end of the tab outlined 110

thereby is to be reached and picked at with the finger nail until the edge thereof is initially elevated to the extent necessary to be grasped between the fingers for the purpose of swinging the tab up and exerting pull thereon to extract the cap from the bottle mouth.

To remedy both of these objections, it has been proposed to depress or compress 10 the pulp board or paper material of the cap in an effort to form a substantial permanent top depression or recess at the free end of the tab outlined by the slit in the top surface of the cap or to define the depressed tab by a depressed groove, but because of manufacturing difficulties and certain characteristics of the paper material of the cap, such compressions have not attained the results sought and have not been 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780

To the uninformed and the uninitiated, the faint barely visible slit in the cap top defining the area of the top of the cap forming the depressed tab, does not suggest the presence of means for extracting the cap and does not explain the operation necessary to elevate such tab to position for grasping by the fingers, and furthermore, even those informed as to the existence and purpose of depressed tabs in these caps, find it exceedingly difficult to gain access to and pick up the free edge of said tab portion even when mutilating and splitting the same.

I have devised a remedy for these difficulties, a solution of the problem, under which the resulting product, the finished cap or closure disk, presents a depressed tab formed to be split by the user from the body of the cap or disk and seated in the recess thus formed flush with the cap top surface, with the free end tip of the tab cut off and removed, forming the tab with a usually straight edge exposed and freely accessible in a substantial clearly visible recess originally occupied by the

end of the tab before such end was severed and removed, and constituting a purpose-indicating open recess exposing the end edge of the tab.

With these and other objects in view, my invention consists in certain novel features and in construction as more fully and particularly set forth and specified herein-after.

Referring to the accompanying drawings, forming part hereof:

Figs. 1, 2, 3, 4, and 5, show in top plan, one piece bottle caps or closure disks embodying my invention in various forms.

Fig. 6 is a section on an enlarged scale 30 on the dotted line 6—6, Fig. 1, dotted lines showing the double pull tab after being split from the cap and bent up by the user.

Fig. 7 is a cross section on the lines 7—7, Fig. 1.

Fig. 8 is a section on the line 8—8, Fig. 5, dotted lines indicating the position of the tab after being horizontally split from the cap and bent up by the user.

Fig. 9 is a top plan view of another form of my invention.

Each cap or closure disk 1, illustrated by the accompanying drawings, consists of a single-ply or one-piece sheet of paper material or board such, for instance, as is commonly employed for bottle caps, possessing the peculiar characteristic of splitting in a plane parallel with its top and bottom faces under certain conditions, while possessing the required tensile and other strength.

This capacity of the sheet forming the disk to split horizontally is utilized to provide a central portion of the disk top capable of being split from the remainder of the disk and bent up to form a relatively-thin pull tab, such as *a*, indicated by dotted lines in Figs. 6 and 8, and by central portion of the disk, I mean any top portion of the disk located within and not extending through the boundary of the disk defined by the peripheral edge of the disk.

This tab forming portion of the disk top is outlined by one or more very thin shallow incisions extending down through the disk top face and approximately half way through the thickness of the paper material sheet forming the disk. The cap is thus incised to provide a tab forming portion within the boundary of the disk having one or two ends that are adapted to be picked up by the finger nail and then pulled up and back to strip or split a relatively thin tab from the remainder of the disk back to the base of the tab or part thereof where the connection between the tab and remainder of the disk is maintained for the purpose of transmitting the extracting pull of the tab to the disk for removal of the disk from the bottle mouth.

The depth of the incision defines the splitting plane and consequently the thickness of the relatively-thin tab split from the disk leaving a top depression in the disk 5 with a preferably imperforate although relatively-thin floor.

The pull connection between the base of the tab and the remainder of the disk can be maintained by any suitable coupling means, 10 or by strengthening means limiting the splitting point, or in some instances, if the tab is of sufficient thickness and strength at its junction with the body of the cap, as in Figs. 5 and 8, added coupling or strengthening 15 means may not be necessary.

A staple 2, driven through the cap and clinched at the underside thereof, can be employed to form tab coupling and strengthening means, and the top bar of this staple 20 is operatively arranged in any suitable manner with respect to the pull tab forming panel outlined by the incision, to perform the desired functions of limiting the split or maintaining the pull connection from the 25 elevated tab to the body of the disk.

Figs. 1, 3 and 9 show the top bar of the staple 2, traversing the base of the tab or tabs and extending down through the disk beyond the side edges of the tab or the opposite sides of the split outlining the same, 30 as in Patent No. 761,005, May 24, 1904, for instance. In Fig. 2, I show the staple 2, traversing the tab portion with its ends driven down through the same, for instance, 35 as the staple is driven through the attached flap in Patent No. 765,049, July 12, 1904.

In the form shown by Figs. 5 and 8, the thin approximate U-shaped incision 3, that outlines the pull tab portion 4, is so deep as 40 to extend almost but not quite through the full thickness of the disk, and as the depth of the incision determines the plane of the split (with respect to the top and bottom faces of the cap) and consequently the thickness of the pull tab *a*, when stripped and split up from the remainder of the disk, such tab will under certain conditions be sufficiently thick and strong where its base merges into the body of the disk as to constitute a cap extracting coupling or connection without the presence of the coupling or strengthening staple or other added means. 45

In the forms shown by Figs. 1, 2, 3, and 6, continuous or unbroken-loop-like shallow 55 incisions 5 are shown that outline elongated double tab portions 6, that can be lifted and split from either or both ends toward the middle to form either a single tab or a double tab, see *a*, Fig. 6. In these forms, an intermediate portion of the elongated panel 6, outlined by the continuous incision 5, is bridged by a staple 2, to form the pull coupling from tab to disk proper.

In the form shown by Fig. 9 an approximate U-shaped shallow incision 7, outlines a

single end tab portion 8, that is adapted to be picked up at one end to form a thin tab that will split or strip from the body of the disk up to the staple 2, that insures the pull connection from tab to disk proper during 70 the extracting operation.

In the form shown by Fig. 4, I show two separate shallow U-shaped incisions 9, arranged in alinement with their open ends in opposition with an intervening staple 2 to 75 cooperate with either or both pull tab panels 10 when either or both is or are picked up at their free ends and stripped or split toward the staple, in maintaining pull connection from tab to disk. 80

In each example described, the thickness of the split off lifted tab and the depth of the floor *b* of the recess or depression formed by thus stripping the tab, is defined by the depth of the incision that defines the tab in 85 the cap top.

In caps incised to define thin portions of the cap to be picked up and split from the body of the cap, it is exceedingly desirable to afford the finger nail free access to the 90 pick up end of the tab to the full depth of the thickness of the tab, i. e. to the floor of the depression in which the tab is located. Otherwise, the finger nail is very liable to start the split in a plane above that 95 in which the incision terminates with the result that the portion split does not produce a tab of the full thickness intended and desired. To produce the elevated pull tab of full thickness and the required tensile 100 strength, the finger nail should have free access to the pick up end of the non-split tab portion, to the full thickness of the end edge of said end so as to avoid initiating a horizontal split in said end and so as to 105 start the split along the horizontal plane in which the tab defining vertical slit terminates.

I accomplish this result, in each bottle cap formation shown, by providing a permanent clearly-visible open-top recess *c*, beyond the pick up end of each tab portion and in depth equal to the full depth of the depression in which such tab portion is located, and hence, in depth equal to the thickness of the tab portion. The floor *b*, of this recess *c*, is hence a longitudinal horizontal continuation of the floor of said depression, and serves as a guide for the finger nail in reaching under the pick up end to initiate 110 the elevating and splitting action thereof without a tendency to start splitting the tab portion itself. The formation of this peculiar permanent recess *c*, in longitudinal continuation of the tab portion and of the depression left by splitting and elevating the tab, exposes the pick up end edge *d*, of the tab portion and renders the same freely accessible, as said edge *d*, forms one vertical 115 wall of the recess or well *c*. 120

I accomplish this desirable result, by making the shallow tab cutlining incision in the cap longer than required for the length of the tab, i. e. the over all length of this incision is equal to the length of the tab and the length or width of the recess c , or of the tab and the two recesses c , in such forms as shown by Figs. 1, 2 and 3.

I then free the extended ends of the tabs 10 and cut off such extended ends to produce tabs of the desired length thereby leaving the permanent recesses and the exposed pick-up edges of the tabs.

In the completed caps, the tab portions 15 are not split from the body of the caps except at their free end portions, say as far back as indicated by the full lines b in Figs. 6 and 8, solely for the purpose of freeing the tab tips to permit severing and removable thereof and to provide a free end portion at the tab edge d , under which the finger nail can catch when guided by the floor b . The tab portions in the completed caps hence form unsplit connected parts of 20 the bodies of the caps, except at the extreme end or tip portions, and are designed to be split by the user when raising the same to perform pull tab functions, although I do not wish to so limit all features of my invention. An advantage is thereby gained 25 as the tab portions forming non separated parts of the caps do not tend to curl up or elevate and form upward projections and do not become deformed, and do not interfere with free capping machine operations, 30 In other words, the caps of my invention completed for the market, will have the tip or end portion of each tab freed or split, the major portion of each tab remaining unsplit 35 and secured or included in its original condition in an unbroken part of the disk. For instance, referring to Figs. 1 and 5, the tip 40 of the tabs are freed or split back to the dotted lines 5^a , 3^a , respectively. In Figs. 45 6 and 8 the tip tab is split or freed the distance of the full line b , and in Fig. 6, the dotted line 5 indicates the plane in which

the slit 5 terminates and, consequently the plane in which the tab will split from the disk when elevated and stripped by the user, 50 and the same remarks apply to the dotted line 3, Fig. 8.

I do not wish to limit myself to any particular steps of the method of making the caps of my invention nor to any particular 55 mechanisms employed in carrying out steps in the manufacture, or to the exact constructions illustrated.

What I claim is:—

1. A one-piece sheet of paper material 60 constituting a bottle cap incised to outline a non-split pull tab horizontally splittable by the user to form a pull tab, the area within the incision being of greater length than the pull tab, the tip portion only of said tab being horizontally split from the body of the cap with the end thereof cut off and removed forming the tab tip with an accessible pick-up edge located down in the open-top recess formed by the removal of said 70 end.

2. A container cap consisting of a paper material disk capable of splitting in a plane between its top and bottom faces, said disk being incised through a portion of its thickness to outline a panel in the top face of the disk designed to provide a pull tab that can be elevated from one end by splitting the disk, the area enclosed by the incision being of greater length than said pull tab, 75 one end of said panel of a thickness equal to the thickness of said tab being cut and split from the disk to form an open-top flat-floor recess and the tab with a pick up edge exposed and accessible throughout its 80 full thickness in said recess, whereby the floor of the recess serves to guide the finger nail in picking up the full thickness of the tab.

In testimony whereof I have hereunto set 90 my hand at Fulton, N. Y., this 22nd day of October, 1924.

WILBUR L. WRIGHT.
